FOOD SEASONING SYRINGE

Samuel L. McNair, Overland Park, Kans., assignor to Dazey Products Company, Kansas City, Mo.

Filed Oct. 17, 1972, Ser. No. 300,399

Term of patent 14 years

Int. Cl. D7—04

U.S. Cl. D7—106

FIG. 1 is a side elevational view of a food seasoning syringe showing my new design;

FIG. 2 is a bottom view thereof;

FIG. 3 is an elevational view from the right or left of FIG. 1; and

FIG. 4 is a top plan view thereof.

I claim:

The ornamental design for a food seasoning syringe, as shown.
